H. W. PLUMMER
Inventor

UNITED STATES PATENT OFFICE.

HENRY W. PLUMMER, OF AUGUSTA, MAINE.

SURGICAL TOURNIQUET.

1,218,313.

Specification of Letters Patent.

Patented Mar. 6, 1917.

Application filed August 28, 1916. Serial No. 117,336.

To all whom it may concern:

Be it known that I, HENRY W. PLUMMER, a citizen of the United States, residing at Augusta, in the county of Kennebec and State of Maine, have invented a new and useful Surgical Tourniquet, of which the following is a specification.

This invention relates to certain improvements in tourniquets or hemostatic bandages and it is an object of the invention to provide a device of this general character of a novel and improved construction whereby the same may be readily and effectively applied to a limb within a minimum of time but with a maximum of efficiency.

It is also an object of the invention to provide a novel and improved device of this general character including a compression member freely movable in one direction but normally held or locked against movement in an opposite direction.

A further object of the invention is to provide a device of this general character including a novel and improved compression member capable of direct endwise thrust in one direction and which is moved endwise in an opposite direction upon axial rotation thereof whereby said second endwise movement is gradual and under control.

A more specific object of the invention is to provide a novel and improved device of this general character which includes a flexible band or strip adapted to be drawn about a limb together with a compression member capable of quick adjustment against an artery so that passage of blood through said artery is obstructed or retarded and whereby said compression member may only be adjusted away from the limb gradually so that the flow through the artery may be again and quickly stopped in the event an operation is not entirely completed.

The invention also consists in the details of construction and in the combination and arrangements of the several parts of my improved tourniquet whereby certain important advantages are attained and whereby the device is rendered simple, inexpensive, and otherwise convenient and advantageous for use, all as will hereinafter be more fully set forth.

The novel features of the invention will hereinafter be definitely claimed.

In order that my invention may be the better understood I will now proceed to de-

scribe the same with reference to the accompanying drawings, wherein—

Figure 1 is a view in side elevation of a tourniquet or hemostatic bandage constructed in accordance with an embodiment of my invention; the band or strip being diagrammatically illustrated;

Fig. 2 is a view in top plan of the device as herein disclosed;

Fig. 3 is an enlarged view in elevation of the block and compression member as herein included, the band or strip being omitted;

Fig. 4 is a sectional view taken substantially on the line 4—4 of Fig. 3;

Fig. 5 is a view in top plan of the device as illustrated in Fig. 3 with the compression member and closure plate removed;

Fig. 6 is a transverse sectional view taken through the locking member coacting with the compression member.

Fig. 7 is a view in plan of the spring included in the locking member as herein embodied.

As disclosed in the accompanying drawings 1, denotes an elongated band or strip, preferably of steel, and which is provided with a plurality of longitudinally spaced knobs 5 for a purpose to be hereinafter more particularly referred to.

One end portion of the band or strip 1 is suitably secured to the block 2 preferably rectangular in form. The block 2 is of a length in excess of the width of the band or strip 1 and the longitudinal axis of said block is perpendicularly related to the longitudinal axis of the band or strip 1 with said band or strip secured to the block midway the length thereof.

The block 1 is provided with the transversely arranged opening 3 through which the free end portion of the band or strip 1 is adapted to be disposed and when said band or strip is drawn about a limb, the knobs 5, hereinbefore referred to, will coact with the side face of said block as indicated at 6, to hold said band or strip against retrograde movement although it will be at once understood that the tension of the band or strip upon a limb may be readily and conveniently relieved by disengaging the knobs from said face of the block. It

will also be understood that when strain is imposed upon said band or strip, the knobs 5 will readily pass through the opening 3.

It is also thought to be self evident that the inherent resiliency of the band or strip 1 will cause a knob carried by a portion of the band or strip extended through the opening 3 and beyond the block 2 to engage with a face 6 of the block 2 in substantially an automatic manner.

The top face of the block 2 is provided with a recess or pocket 13, preferably rectangular in form and which has in communication therewith an opening 13^a disposed through the block and having a smooth bore and loosely disposed through the opening 13^a is the endwise movable compression member 7 having in swivel connection with one end thereof, as at 10, the parti-spherical head or knob 9 adapted to be pressed firmly against the flesh to close an artery when the device is in applied position upon the limb.

20 The intermediate portion of the compression member 7 is provided with the beveled threads 7^a which permit the member 7 to freely pass through the locking member 14 when it is desired to force the head or knob 9 into contact with the flesh.

As herein embodied the locking member 14 comprises two separated sections adapted to engage with the threads 7^a and which are normally maintained in such engagement through the medium of the spring 15 coacting with the peripheries of the sections as is believed to be fully shown in Fig. 6 of the accompanying drawings. As herein embodied, the spring 15 comprises a split ring 35 formed of resilient material. It is also to be noticed, as illustrated in Figs. 5 and 6 of the accompanying drawings, that the portions 16 of the sections of the member 14, engaging with the threads of the member 7 40 having their upper surfaces beveled and which coact with the beveled portions of the thread to assure an unobstructed movement of the member 7 toward the limb.

It is preferred that the sections 14^a of the locking member be semi-circular with their apposed straight edges provided with registering semi-circular recesses 14^b whereby an opening is afforded through which the member 7 is directed.

50 It is also to be noted that the coaction between the member 14 and the threads 7^a of the member 7 is such as to permit movement of the head or knob 9 away from the limb only upon requisite axial rotation being given to said member 7 and for which reason the outer end of said member 7 is provided with the operating member 8, herein disclosed as a circular head having its periphery serrated or knurled for obvious reasons.

60 A material advantage is afforded by the particular manner in which the member 7 is operated as a quick and unobstructed endwise movement may be given to the member to cause the same to impose the proper pressure upon an artery when the device is ap-

plied to a limb and the member 14 holds the same normally against retrograde movement. The outward movement of the member 7, as afforded by the axial rotation thereof, assures a gradual release of the pressure upon an artery so that in the event an operation is not entirely successful, the pressure upon the artery can be quickly restored without undue injurious effect upon the patient.

The outer or open face of the recess 13 is adapted to be closed by the removable closure plate 12 held in applied position by the screws 11 or other suitable means and it will be understood that said plate is provided with a suitable opening through which the member 7 is freely movable in either direction.

I also find it of advantage to provide the free end portion of the band or strip 1 with a suitable opening 4 to afford means whereby a finger or a suitable implement may be engaged with the band or strip to assure said band or strip being engaged around a limb with a maximum of pressure thereon.

From the foregoing description, it is thought to be obvious that a tourniquet constructed in accordance with my invention is of an extremely simple and comparatively inexpensive nature and is particularly well adapted for use by reason of the convenience and facility with which it may be assembled and employed, and it will also be obvious that my invention is susceptible of some change and modification without material departure from the principles and spirit thereof and for this reason I do not wish to be understood as limiting myself to the exact construction and arrangement of the several parts herein shown in carrying out my invention in practice except as herein-after claimed.

I claim:

1. A tourniquet consisting of a block, a limb embracing compression band coacting with the block, a compression member disposed through said block and having unobstructed direct endwise movement in one direction, said member being operable independently of the band, and automatic means for holding said member against movement in an opposite direction.

2. A tourniquet consisting of a block, a limb embracing compression band coacting with the block, a compression member disposed through said block and having unobstructed direct endwise movement in one direction, said member being operable independently of the band.

3. A tourniquet consisting of a block, a limb embracing compression band coacting with the block, a compression member loosely disposed through said block and operable independently of the band, and means for retarding the movement of said compression member in one direction.

4. A tourniquet consisting of a block, a limb embracing compression band, a compression member disposed loosely through the block and provided with beveled threads, 5 and a locking member carried by the block and including relatively movable members normally in engagement with said threads.
5. A tourniquet consisting of a block, a limb embracing compression band, a compression member loosely disposed through the block and provided with beveled threads, 10 a locking member carried by the block and comprising relatively movable members normally in engagement with the threads, and 15 yieldable means for maintaining the last named members in their normal positions.
6. A tourniquet consisting of a block, a limb embracing compression band coacting with the block, and a compression member 20 carried by said block and having unobstructed movement in one direction and movable in an opposite direction upon axial rotation of the member.
7. A tourniquet consisting of a block, a limb embracing compression band coacting 25 with the block, a compression member carried by said block and having unobstructed movement in one direction, said member being movable in an opposite direction upon axial rotation of the member, and a head 30 swiveled to said member.
8. A tourniquet consisting of a block provided with an opening therethrough, and a flexible band secured at one end to the block
- the free end portion of the band being insertible through the opening of the block said band being provided with protuberances coacting with the block for holding the band against retrograde movement when inserted through the opening. 35
9. A tourniquet consisting of a block provided with an opening therethrough, a resilient flexible band secured to said block and insertible through the opening of the block said band being provided with protuberances coacting with the block for holding the band against retrograde movement when inserted through the opening. 40
10. A tourniquet consisting of a block, a limb embracing compression band, a compression member disposed loosely through the block and provided with beveled threads, 45 and an expansible locking member coacting with the block and the threads of the compression member. 50
11. A tourniquet consisting of a block, a limb embracing compression band, a compression member disposed loosely through the block and provided with beveled threads, a locking member coacting with the block 55 and the threads of the compression member, said locking member comprising two pivotally connected members, and spring means coacting with said members for maintaining said members normally in engagement with the threads of the compression member. 60
